UNITED STATES PATENT OFFICE.

ADOLPH ANDERSON, OF WEST ALLIS, WISCONSIN.

CARD HOLDER.

1,423,294.

Specification of Letters Patent. Patented July 18, 1922.

Application filed May 23, 1921. Serial No. 472,006.

To all whom it may concern:

Be it known that I, ADOLPH ANDERSON, a citizen of the United States, and resident of West Allis, in the county of Milwaukee and

5 State of Wisconsin, have invented certain new and useful Improvements in Card Holders; and I do hereby declare that the following is a full, clear, and exact description thereof.

10 My invention refers to card or ticket holders, wherein a series of tickets are printed upon a single slip, and it has for its primary object to provide a simple, economical, one-piece metallic skeleton jacket for such tickets, the same being open at its ends and having its opposite walls convexed to form yielding friction surfaces, whereby the tickets are held in place.

Another object of my invention is to provide 20 companion openings in the convex walls, whereby the tickets can be positively fed towards either end of the jacket.

Still another object of my invention is to provide the end edges of the jacket with 25 companion straight cutting surfaces, which cutting surfaces are intersected centrally by recesses, whereby the tickets or cards are exposed forwardly and backwardly of the cutting edge to visualize the same, in order that 30 they may be approximately severed at their division line. Obviously, the card-holder may be constructed from any thin sheet metal, such for example as aluminum or the like, it being understood that the device 35 can be either formed from a flat blank folded upon itself and seamed at one edge, or from tubular sections cut to proper lengths and compressed to the desired formation in cross-section, provision being made for the 40 operation of suitable dies, whereby the central openings and end recesses, in connection with the cutting edges, may be formed simultaneously.

With the above objects in view, the invention 45 consists in a new article of manufacture as herein described in connection with the accompanying illustrations and subsequently claimed.

In the drawings:

50 Figure 1 represents a plan view of a card-holder embodying the features of my invention, with portions broken away to more clearly illustrate structural features, the same being shown with a card or series of 55 tickets fitted therein, and

Figure 2 is a cross section of the same.

Referring by characters to the drawings, 1-1 represent the side walls of the jacket, which side walls are exteriorly convexed toward their center portions so as to approximately engage each other upon their inner surfaces, and to thus form a yieldable friction grip for the card. The longitudinal edges of the jacket are, as shown at 2-2, folded in the form of open loops, so as to 60 prevent breaking of the metal at the fold, and also to form free runways for the edges of the card.

The side walls 1-1 are provided with central apertures 3-3. The open ends of 70 the jackets are cut at right angles to the side edges to form companion straight line upper and lower cutting edges 4-4, which cutting edges are intersected by central recesses 5, the same being extended inwardly or back 75 of the cutting edges so as to present an unobstructed view of the card or ticket thereunder, whereby the ticket, when fed to the cutting edge, is brought to a position in approximate alignment with said cutting edge, 80 in order that it may be severed correctly. The central apertures, formed in the side walls of the jacket, are for the purpose of convenient access to the ticket or tickets, whereby the operator, by simply placing the 85 thumb and first finger upon the ticket, through the aperture, can feed said ticket forward to the cutting line. The apertures also facilitate manipulation of the ticket or card, whereby it can be properly inserted 90 within the jacket.

Obviously an article of this kind can be readily carried in the pocket, and there is no liability of the tickets being lost. Furthermore, they can be quickly severed, and due 95 to the fact that they are confined in a flat plane, there is slight liability of cutting off two tickets at a time, should said tickets be folded into a double layer, without the party so cutting the tickets be aware of the fact. 100

The holder can be made from a tubular pipe cut into the desired lengths, and flattened, or it can be made in a single blank and folded with the meeting edges lapping at the longitudinal face of the structure 105 and soldered or welded. It will be observed that the concavo convex walls, in yielding connection, will thus prevent the tickets from inadvertently dropping out of the jacket, there being sufficient friction, so as 110 to firmly hold them, except in instances where they are positively fed out by the op-

erator grasping opposite walls of the cord or ticket through the fed apertures 3.

While I have shown and described a simple exemplification of my invention in 5 all of its details, it is understood that I may vary the structural features within the scope of the claims.

While I have shown and described the tubular holder as having both ends open, 10 obviously I may without departing from the spirit of my invention close one end, whereby the device will assume the form of a pocket or case.

I claim:

15 1. A card or ticket holder comprising a flattened tubular section open at its ends, the side walls of which sections are centrally apertured and concavo convex so as to

form inner longitudinal gripping surfaces for the tickets or card, the longitudinal 20 edges being folded to form loops, and the end edges of the jacket being formed with straight cutting surfaces intersected by central recesses.

2. A card or ticket holder comprising a 25 flattened tubular section open at its ends, the side walls of which jacket are bowed inwardly to form friction grips for tickets or cards, the said side walls being centrally apertured, and the end edges terminating 30 with straight companion cutting surfaces.

In testimony that I claim the foregoing I have hereunto set my hand at Milwaukee, in the county of Milwaukee and State of Wisconsin.

ADOLPH ANDERSON.
